Primary Examiner—Jeffrey Asch
Attorney, Agent, or Firm—James G. O'Neill[57] **CLAIM**

The ornamental design for a cylindrical housing for a telephone paystation, as shown and described.

DESCRIPTION

FIG. 1 is a top plan view of FIG. 2;

FIG. 2 is a front elevational view of a first embodiment of a cylindrical housing for a telephone paystation showing my new design;

FIG. 3 is a right side elevational view of FIG. 2;

FIG. 4 is a bottom plan view of FIG. 2;

FIG. 5 is a rear elevational view of FIG. 2;

FIG. 6 is a left side elevational view of FIG. 2;

FIG. 7 is a front elevational view of a second embodiment of a cylindrical housing for a telephone paystation, illustrating my design; and,

FIG. 8 is a front elevational view of a third embodiment of a cylindrical housing for a telephone paystation, illustrating my design.

The sides, top, bottom, and rear as shown in FIGS. 1 and 3-6 are the same for all three embodiments.
